CLAIM

The ornamental design for a shroud with upper stabilizer arms for patient interface, as shown and described.

DESCRIPTION

FIG. 1 is a front perspective view of a shroud with upper stabilizer arms for patient interface showing our new design; FIG. 2 is a front view thereof; FIG. 3 is a rear view thereof; FIG. 4 is a top view thereof; FIG. 5 is a bottom view thereof; FIG. 6 is a left side view thereof; FIG. 7 is a right side view thereof; FIG. 8 is reverse perspective view thereof; and, FIG. 9 is an exploded view thereof within the unclaimed environment of a cushion module and an elbow. The broken ones in the drawings depict portions of the patent interface that form no part of the claimed design.

(Continued)

The dotted broken lines in the drawings depict the boundary of the claim and form no part of the claimed design.
